(57) **CLAIM**

The ornamental design for a watch strap, as shown and described.

DESCRIPTION

FIG. 1 is a bottom view of the invention;

FIG. 2 is a top view of the invention;

FIG. 3 is a perspective view of the invention;

FIG. 4 is a side view of the invention; and,

FIG. 5 is another side view of the invention, showing the side opposite that shown in FIG. 4.

The bottom structure of the watch strap that is shown in broken lines in the drawings is for illustrative purposes only and does not form part of the claimed design.
